SUSPENDING DEVICE FOR CALENDARS AND LIKE ARTICLES

Filed March 6, 1929

INVENTOR,

Oscar Regen

BY

Henry J. Luecke,
HIS ATTORNEY.

UNITED STATES PATENT OFFICE

OSCAR REGEN, OF BROOKLYN, NEW YORK

SUSPENDING DEVICE FOR CALENDARS AND LIKE ARTICLES

Application filed March 6, 1929. Serial No. 344,836.

This invention relates to suspending devices for calendars and like articles.

Pursuant to the present invention, the suspending device comprises a member such as a bow or the like of fabric or other suitable material serving as an anchorage as well as to impart ornamentation, and a member in the form of a loop slidably or otherwise loosely secured to the anchorage member, said loop member including a length of wire, the ends of the loop member being knotted or otherwise formed to provide an enlargement, serving when positioned on the calendar or the like to lock the suspending device.

15 My invention is particularly applicable for calendars and like articles usually provided with a suspending opening. My suspending device is positioned by inserting the wired end of the loop through the opening to locate 20 the bow or other ornamented anchorage member on the front face of the calendar, whereafter the loop is pulled to bring its knotted or other enlarged portion into engagement with the rear face of the calendar, whereupon the 25 suspending device is locked in position and whereby the portion of the loop free from any visible knot or other enlargement is employed for suspending the calendar from a nail or like support.

30 Further features and objects of the invention will be more fully understood from the following detail description and the accompanying drawings, in which:

Fig. 1 is a perspective view of one form of 35 my suspending device embodying a bow, in a form as supplied to the trade;

Fig. 2 is a perspective view showing one manner of applying my suspending device to a calendar or like article;

40 Fig. 3 is a rear view of a calendar or like article having my suspending device shifted to locking position and the loop ready for suspension; and

Fig. 4 is an enlarged view of a preferred 45 form of combined wire and fabric serving as the material for the loop member.

Referring to the drawings, the front or anchorage member 10 may be in the form of an ornamental bow as indicated, or may be 50 of any other desired configuration; such

ornamental member may be formed of fabric, celluloid or other suitable material. A bow or the like lends itself readily to the application of my invention by reason of the provision of the central looped portion 10a of the bow for receiving the loop member 11.

In the most preferred forms of the loop member, the same is formed with wire cores 12, 13, Fig. 4, which are woven to be encased within fabric of suitable character, which composite material is readily manufactured in cord form of indefinite length.

A suitable length of the loop member 11 is cut off, and a knot formed adjacent the ends 14 of the loop member, as is indicated 65 at 15, see Fig. 1.

My suspending device as supplied to the trade is illustrated in Fig. 1.

For application of my suspending member to a calendar 16, or the like, see Fig. 2, usually provided with a suspension opening 17, the wire-stiffened free ends 14 of my loop member 11 are inserted through such opening 17 and the loop member 11 pulled to bring the anchorage or front member 10 into contact 70 with the front face of the calendar or like article 16, as is indicated in Fig. 3, whereafter the loop member 11 is grasped at an intermediate portion of one of its lengths, to slide the loop relative to the looped portion 10a of the front member 10 until the knot 15 of the loop member 11 has been brought 75 into contact with the rear face of the calendar or other article 16. The knot 15 and the ends 14 of the loop member 11 are thus 80 brought to a location of concealment, namely, at the rear face of the calendar or other article 16 and the intermediate portion of the loop member 11 is available for suspending 85 the calendar or other like article from a nail or other suitable support, in the usual manner.

Whereas, I have described my invention by reference to specific forms thereof, it will 90 be understood that many changes and modifications may be made without departing from the spirit of the invention.

The appended claims serve to define the scope of the invention.

I claim:—

1. A suspension device for a calendar and like article provided with a suspension opening, comprising a front member and a loop member slidably carried by said front member, said loop member being of yieldable material and including a reinforcing element, said loop member having an enlarged portion.
- 5 2. A suspension device for a calendar and like article provided with a suspension opening, comprising a front member and a loop member slidably carried by said front member, said loop member being formed of cord material embodying wire at its free ends, said loop member being knotted adjacent its free ends.
- 10 3. A suspension device for a calendar and like article provided with a suspension opening, comprising a front member and a loop member slidably carried by said front member, said loop member being formed of cord material having wire encased therein, said loop member being knotted adjacent its free ends.
- 15 4. A suspension device for a calendar and like article provided with a suspension opening, comprising a front member and a loop member slidably carried by said front member, said loop member being formed of cord material and having an enlarged portion adjacent its free ends, the cord material at said free ends being re-inforced by a stiffening element.
- 20 5. A suspension device for a calendar and like article provided with a suspension opening, comprising a front member and a loop member slidably carried by said front member, said loop member being of cord material, said cord material being enlarged and stiffened at one portion thereof.

In testimony whereof I have signed this specification this 5th day of March, 1929.

OSCAR REGEN.
